UNITED STATES PATENT OFFICE.

ANNA R. WOLVERTON, OF LOS ANGELES, CALIFORNIA.

NEEDLE.

Application filed June 11, 1923. Serial No. 644,758.

To all whom it may concern:

Be it known that I, ANNA R. WOLVERTON, a citizen of the United States, residing at Los Angeles, in the county of Los Angeles and State of California, have invented new and useful Improvements in Needles, of which the following is a specification.

This invention relates to needles, and particularly to a needle having hook ends, and which needle is adaptable for drop stitch work in the repairing of silk hosiery and the like.

The invention has for an object the provision of a device of this character which is simple of construction, easy to use and which performs the function required of it neatly and rapidly.

With the above and other objects in view, the invention consists in the novel and useful provision, formation, construction, association and relative arrangement of the elements of the needle, all as shown in one embodiment of the accompanying drawings, described generally, and finally pointed out in the claims.

In the drawings:

Figure 1 is a view illustrating hosiery in which there is a "run."

Figure 2 is a side view showing the improved needle, the same being on an enlarged scale;

Figure 3 is an enlarged fragmentary view showing use of the needle in repairing the "run" in the hosiery shown in Figure 1;

Figure 4 is a cross section on the line 4—4 of Figure 2; and

Figures 5 to 10 inclusive illustrate the use of the device in repairing a "run" in hose, such as shown in Figure 1.

Corresponding parts in all the figures are designated by the same reference characters.

Referring with particularity to the drawings, the hosiery of Figure 1 is designated by A, and in which hosiery it will be noted that there is a "run" at the point marked 1, in which the woof threads have become separated from the warp threads, with usual appearance of sheds. The present device is particularly adaptable for repairing

50 "runs" and said device is designated by B, which device B comprises a needle having a uniformly tapering cross section from a point of maximum diameter shown at 2, and said cross section is circular, as shown in Figure 4. The needle uniformly tapers from the point of maximum cross

sectional areas, namely, the point 2, downwardly to the neck portions 3 and 4 of two hooks 5 and 6, said hooks being reversed, as shown in Figure 2.

The operation, uses and advantages of the device are as follows:

Referring to Figure 1 it will be seen that there is a short loop 7 at the bottom of the "run" in the hosiery. This loop 7 is illustrated in Figure 5. We first slip or pass, say the hook 5 through this loop and pull upwardly on the hook so as to stretch the loop or distend it slightly, whereupon the needle is passed straight downwardly through this loop and the hook 6 is moved to engage the warp thread 8, as shown in Figure 6. The needle now retreats bringing the bight of the thread 8 with it through the loop 7 and thus forming a second loop; this being shown in Figure 8, the catching of the thread 8 being shown in Figure 7. In Figures 7 and 8 it is noted that the needle is revolved to the right in the drawing of the thread 8 through the loop 7. The needle is now slipped through the loop formed by the thread 8 and in doing so the loop is forced to slide over the uniformly tapering body of the needle, and this distends the loop slightly. The needle now assumes the position shown in Figure 9 and the hook 5 which is reversed from the hook 6, is ready to engage the next woof thread 9, which engagement is shown in Figure 10 at 10. The operation is then repeated, commencing from the showing in Figure 6 on.

It is evident from this brief description that the needle is continuously revolved and that a series of loops are formed, one loop passing through a previously formed loop to form a connected series of loops. The needle by having a uniformly tapered cross section acts to distend the loop when the said loop is slid over the needle, and so that the next woof thread is easily drawn through said loop to form another loop and so on.

Figure 2 illustrates a series of woof threads and shows how the needle forms a greater shed when between two of such threads.

In Figure 3 we have on an enlarged scale the result of a series of operations substantially as shown in Figures 5 to 10 and in which we have a series of connected loops, as shown at 11, with the needle B in the

process of forming loops with the next adjacent woof threads.

With a device of this character it is an extremely simple operation to repair any "run" in silk hosiery, so that it assumes its former appearance, and the present needle by having a reverse hook only requires that an operator continuously turn the needle with the cast loop of each ascending woof 10 thread slipped over the needle and to close up the shed between the woof threads.

Having thus disclosed my invention, I claim and desire to secure by Letters Patent.

15 As a new article of manufacture adapted

to pick up drop stitches in hosiery, including a member provided with means for engaging a first woof thread, and a further member for engaging a second woof thread upon a turning of such member to loop the 20 first woof thread with the second woof thread.

In testimony whereof, I have signed my name to this specification in the presence of two subscribing witnesses.

ANNA R. WOLVERTON.
